UNITED STATES PATENT OFFICE.

LEWIS P. NICHOLS, OF CLEVELAND, OHIO.

DESIGN FOR A GAME BOARD.

Application filed September 23, 1926. Serial No. 19,152. Term of patent 14 years.

To all whom it may concern:

Be it known that I, LEWIS P. NICHOLS, a citizen of the United States, residing at Cleveland, in the county of Cuyahoga and State of Ohio, have invented a new, original, and ornamental Design for Game Board, of which the following is a specification, reference being had to the accompanying drawing, forming part thereof.

The figure is a plan view of a game board, showing my new design.

I claim:

The ornamental design for a game board, as shown.

LEWIS P. NICHOLS.
